DUPLICATOR

Truman L. Butterfield, Middlebury, Vt.

Application September 18, 1937, Serial No. 164,597

6 Claims. (Cl. 101—131)

This invention relates to an improved duplicator more particularly intended for use in making copies of typewritten or like matter.

One object of the invention is to provide a duplicator employing a spring impressing plate which serves the dual function of providing anchoring means for the gelatin pad employed and also, in closed position, defining a top wall for the duplicator.

10 Another object of the invention is to provide a duplicator employing a clamp which will be effective for separating a sheet of paper from the gelatin pad after contact of said paper with the gelatin pad.

15 A further object of the invention is to provide a duplicator having a drawer serving as a compartment for gelatin pads not in use and for other equipment.

20 A still further object of the invention is to provide a device of this character wherein the spring impressing plate will have means thereon for effectively locking a gelatin pad in operative position underlying its lower surface.

25 And the invention seeks as a still further object, to provide a duplicator which will be characterized by the greatest simplicity and utility and which may be manufactured at an attractive figure.

30 Other and incidental objects of the invention, not hereinbefore called to attention, will render themselves apparent as the description of the invention proceeds.

35 In the drawings forming a part of my application:

Figure 1 is a perspective view of my improved duplicator and showing it with the spring impressing plate in position ready for making an impression or copy on a sheet of paper.

40 Figure 2 is a longitudinal sectional view of the device.

Figure 3 is a horizontal sectional view on the line 3—3 of Figure 2, looking in the direction indicated by the arrows.

45 Figure 4 is a detail top plan view particularly showing the clamp structure employed.

Figure 5 is a detail sectional view on the line 5—5 of Figure 4, looking in the direction indicated by the arrows.

50 Figure 6 is a bottom plan view of the spring impressing plate and showing said plate as it would appear with a gelatin pad mounted thereon before clamping said pad in operative position.

55 Figure 7 is a detail sectional view on the line

7—7 of Figure 6, looking in the direction indicated by the arrows.

Referring now more particularly to the drawings, the numeral 1 indicates in general the preferably rectangular shaped metal body of my improved duplicator. As will be seen, particularly in Figures 1 and 2 of the drawings, the body includes end walls 2 and 3, a bottom wall 4, and side walls 5 and 6. The wall 5 is cut away throughout the major portion of its length and height to define the open end of a compartment 7 adapted slidably to receive a drawer 8. The drawer 8 is provided with a front wall 9 which, in closed position, is adapted to cooperate with the wall 5 for defining a closed side for the body. The body 1 is also provided with an intermediate wall 10 extending throughout the length of the body and serves both as a top wall closing the drawer at its upper side when said drawer is in closed position and also as an impressing base, in a manner to be presently described. As will be seen, the intermediate wall is disposed below the upper edges of the end walls 2 and 3 and the side walls 5 and 6 at a distance substantially one-fourth the depth of said walls so as to define a pad receiving recess 11.

Removably received in the pad receiving recess 11 is a preferably soft rubber pad 12 which extends throughout the major portion of the length of the area of the recess. Extending across one end of the pad in the recess is a laterally disposed block 13 which is secured to the intermediate wall by means of a stud 14. Overlying the block 13 and having its top surface in substantially the same horizontal plane with the top surface of the pad 12, is a preferably rubber strip 15.

Associated with the body 1 is a spring impressing plate, indicated in general at 16. The spring impressing plate is normally of arcuate formation throughout the major portion of its length but is formed with a relatively short straight portion 17 near its free end. The plate 16 carries a mounting block 18 at its inner end and said mounting block is provided with trunnions 19 which extend through the walls 5 and 6 near their upper extremities and near the end wall 2 for swingingly mounting the plate on the body. The mounting block 18 is secured to the under side of the inner end portion of the plate 16 by means of studs 20. Carried at the free end of the plate is a preferably U-shaped handle 21 which has its arms flattened at their inner corresponding ends, as shown at 22, and appropriately secured to the free end portion of the plate 55

16 by means of studs 23. The free end portion of the plate is rolled at 24 to provide reinforcement for said free end of the plate.

As best seen in Figure 6 of the drawings, the 5 spring impressing plate is provided at its under surface, and near its inner end portion, with a pad mounting strip 25 which is formed with a series of laterally spaced upwardly offset hooks 26 which extend inwardly in the direction of the 10 block 18. The strip 25, as will be seen, is fixed on the plate 16, and said strip is held on said plate by means of rivets 27. Slidably mounted on the opposite end portion of the spring impressing plate 16 is a movable pad mounting strip 28. The strip 28 is adapted for longitudinal sliding movement on the under surface of the plate 16 and is provided with upwardly and outwardly extending hooks 29. As best seen in Figures 6 and 7 of the drawings, the strip 28 is 15 extended laterally past the side edges of the plate 16 and said laterally extended portions are bent into U-shape, as shown at 28', and said U-shaped portions have their free ends terminating in overlying relation to the upper margin of the plate 16. The strip 28 will, as will be understood, be 20 permitted to slide longitudinally of the plate 16 but will be limited against separation vertically or laterally by the portions 28'. In order to shift the strip 28 for a short distance longitudinally of 25 the spring impressing plate 16, I provide toggle latches 30 and 31 which comprise handle sections 32 and 33, which handle sections are provided with finger lugs 34 and 35. The toggle latches also include operating sections 36 and 37 which are pivotally connected to the sections 32 and 33 and to the U-shaped portions 28'. The handle sections 32 and 33 have their inner ends 30 connected to the plate 16. It will be understood that by pulling the toggle latches outwardly away 35 from the side edges of the plate 16, the strip 28 will be caused to move rearwardly longitudinally of said plate 16 for bringing said strip 28 closer to the strip 25. By pressing the toggle latches inwardly to a point where the finger lugs engage 40 the side edges of the plate 16, the strip 28 will be moved outwardly or away from the strip 25, for a slight distance along the plate 16 to locked position. Normally carried adjacent the under 45 surface of the plate 16 and extending throughout its length is a gelatin pad 38 which, as will be seen, comprises a main portion 39 and reinforced end portions 40 and 41. The pad 38 is provided, adjacent the reinforced end portions 40 and 41, with series of laterally spaced openings 42 and 50 43 adapted for removable engagement by the hooks 26 and 29 respectively, said hooks being adapted to engage through the openings and overlap the reinforced end portions 40 and 41 respectively. The gelatin pad is mounted in position on the plate 16 by first engaging the hooks 55 26 through the openings 42 and then engaging the hooks 29 through the openings 43, it being assumed that the toggle latches 30 and 31 have been swung outwardly for retracting the strip 28 along the plate 16, as shown in Figure 6. After 60 the hooks 29 are in the openings 43, the latches are forced inwardly, as shown in Figure 1, for tightening the gelatin pad against the under surface of the spring impressing plate 16, as shown in Figure 2, so that the gelatin pad is then ready for use.

My improved duplicator includes a paper clamp which is best illustrated in Figures 1, 2, 4 and 5 of the drawings. The paper clamp is indicated 75 generally at 44 and includes a movable clamp

element 45 which is substantially U-shape. A mounting element serves effectually to mount the element 45 and said mounting element includes an attaching portion 46 which is secured to the under surface of the intermediate wall 10. The mounting element is formed at its free ends with hinge portions 47 which are hingedly connected to mating portions 53 in the element 45 by means of hinge bolts 52. A clamping plate 51 is secured to the inner ends of the element 45 and said clamping plate is adapted to clamp a sheet of paper in such a way that the sheet of paper will be separated from the gelatin pad when the same has been permitted to swing away from the pad 12. A spring 48, which surrounds one of the hinge bolts 52, serves to retain the clamping plate in clamping position.

In order to retain the plate 16 in downward position, when not in use, and thus cause said plate to define a top wall for the device, I provide 20 a latch 54 which is swingingly mounted on the end wall 3 and is adapted to engage over the free end portion of the plate 16.

In use, the drawer 8 will be employed for keeping gelatin pads not in use, as well as other equipment. The drawer will be provided with a suitable lock.

After the gelatin pad 38 has been mounted on the under surface of the plate 16 in the manner set forth, a sheet of typewritten matter which 30 it is intended to copy, is placed, face up, on the soft rubber pad 12. The clamp elements 45 and 49 are shifted for engaging the clamping plate 51 with the upper margin of the sheet for clamping said sheet between the strip 15 and said plate 51. 35 The handle 21 is then engaged and the plate 16 is forced downwardly against its own tension for forcing the gelatin pad 38 into overlying relation with the paper sheet. The gelatin pad 38 is engaged with the paper with sufficient force so 40 that said gelatin pad will have transferred there-to an impression of the typewritten matter on the sheet. The handle 21 is then released and the spring impression plate 16 will spring upwardly under its own tension. The paper clamp 44 will 45 effectually retain the sheet of paper in overlying relation to the pad 12 so that said sheet will be effectively separated from the gelatin pad 38. The sheet of paper bearing the typewritten matter is then removed and a blank sheet of paper 50 on which a copy of the printed matter is to be made, is placed in overlying relation to the pad 12. The spring impression plate 16 is then again forced downwardly against its tension, which tension will, preferably, offer a resistance of about 55 four pounds so that the gelatin pad 38 will be engaged with the blank sheet of paper with a force sufficient to transfer an impression from the gelatin pad to the paper. After the impression has been made, the handle 21 is released and 60 the plate 16 will spring upwardly. The paper clamp 44 will be employed for holding the sheet of paper in place so that the same will be effectively separated from the gelatin pad when the handle is released. As many copies of the subject 65 matter on the gelatin pad as desired may be made merely by repeating the operation for each copy desired.

The gelatin pad may be readily removed by releasing the toggle latches and permitting the 70 strips 25 and 28 to move toward each other for freeing the hooks 26 and 29 respectively for

The spring 48 will be effective in restraining the surface of the spring impressing plate 16. allowing the pad to be removed from the under 75

clamp elements of the paper clamp 44 when it is desired to clamp a sheet of paper in place for any period of time.

Feet, such as shown at 55, are positioned on 5 each corner of the body for spacing the body from a surface on which it rests.

Attention is particularly directed to the fact that the spring impressing plate 16 will be of such formation and afford such tension that uniform engagement of the gelatin pad with the 10 paper on which the impression is to be made will be assured.

It will be understood that my improved duplicator may be made in any size and shape desired 15 so that I do not limit myself in these respects. It is thought that further description of my duplicator is unnecessary.

Having thus described the invention, what I claim is:

20 1. A duplicator including a body, a pad in the body having its upper face exposed and adapted to receive a sheet of paper, a block at one end of said pad seated in said body, a clamp normally retaining the sheet of paper on the pad and consisting of a U-shaped handle pivoted to the body with its arms projecting inwardly and carrying a clamping strip disposed over said block for gripping and holding an end of a sheet of paper, a spring impressing plate carried by the body, and 25 a gelatin pad carried by the spring impressing plate, said spring impressing plate being adapted to be shifted for engaging the gelatin pad with the paper whereby an impression of printed matter on the pad will be made on the paper.

30 2. In a duplicator, a body having side and end walls and a bottom wall, an intermediate horizontal wall for said body disposed below the upper edges of the side and end walls and cooperating therewith to define a pad receiving recess, a pad in said recess, a block in said recess between the pad and one end wall, a paper clamp carried by said end wall and movable into and out of position to overlap the block and hold a sheet of paper against the pad and block, a spring impressing plate, a gelatin pad adapted to have an impression thereon, means connecting the gelatin pad with the plate, and means swingingly connecting the plate with the body at the opposite end thereof from said clamp, said plate being adapted to be shifted downwardly for engaging the gelatin pad with a sheet on said first mentioned pad whereby an impression will be communicated to said sheet.

35 3. In a duplicator, a body having a pad receiving recess, a pad in the recess, a lateral block in the recess, a strip carried by the block, said pad being adapted to receive a sheet of paper in overlying relation to said pad and strip, and a paper clamp carried by the body and being adapted for retaining the sheet of paper against displacement.

40 4. In a duplicator, a body, a pad carried there-

by and being adapted to receive a sheet of paper, a paper clamp carried by the body and having a movable clamp element, said movable clamp element having a clamping plate engageable with the sheet for retaining said sheet of paper on the pad, a spring impressing plate, means connecting the spring impressing plate with the body, a handle for the spring impressing plate, a gelatin pad, means removably connecting the gelatin pad with the plate, and means carried by the 10 body for retaining the plate in downward closed position whereby said plate will define a top for the duplicator, said plate and gelatin pad being shiftable from arcuate position to a position overlying the sheet of paper for transferring an impression of printed matter from the gelatin pad to the sheet.

45 5. In a duplicator, a spring impressing plate adapted to be shifted to a position to overlie a sheet of paper in a body, a gelatin pad, a fixed mounting strip connecting one end of said gelatin pad to one end of the plate, a movable pad mounting strip carried by the other end of the plate and being adapted for removably connecting the end of the pad remote from said first mentioned end of the plate, said movable strip having its ends bent to form hooks overlapping side edges of the plate and slidably mounting the strip, and toggle latches pivoted to the plate and the hooks of the last mentioned mounting strip 30 and being adapted for shifting said last mentioned mounting strip to a position for clamping the gelatin pad on the spring impressing plate, said gelatin pad being adapted to place an impression of printed matter on the sheet of paper. 35

6. In a duplicator, a spring impressing plate adapted to be carried by a body and sprung under tension to a position overlying a sheet of paper in the body, a fixed pad mounting strip having hooks, said fixed pad mounting strip being carried at one end of the plate, a movable pad mounting strip having U-shaped members at its ends slidably connecting it with the opposite side edge portion of the spring impressing plate, toggle latches carried by the spring impressing plate and the U-shaped members of the last mentioned strip and being shiftable from a position laterally of the spring plate to a retracted position over the plate for sliding said last mentioned strip slightly longitudinally of the plate, 50 said last mentioned strip having hooks, and a gelatin pad having a series of openings engageable by the hooks of said strips and being adapted to be stretched by inward movement of the toggle latches and consequent longitudinal movement of the movable pad mounting strip for effectively mounting said gelatin pad on the spring impressing plate, said gelatin pad being adapted to make an impression on the sheet of paper in the body of printed matter on said gelatin pad. 55
